MACHINE FOR MANUFACTURING UNDER-CUT SAND MOLDS

Frank H. Le Jeune, Detroit, Mich., assignor to
 Kelsey-Hayes Wheel Company, Detroit, Mich.,
 a corporation of Delaware

Application August 3, 1936, Serial No. 94,084

1 Claim. (Cl. 22—24)

The invention relates to machines for forming undercut grooves in sand molds and has for one of its objects the obtaining of a simple construction of manually operable mechanism for accomplishing this purpose. The invention has for another of its objects to provide an improved construction of combined presser and cutter head. To this end the invention consists in the construction as hereinafter set forth.

10 In the drawings:

Figure 1 is a vertical central section through the machine;

Figure 2 is a plan view thereof;

Figure 3 is an end elevation;

15 Figure 4 is an enlarged view of a portion of Figure 2 showing the construction of the grooving mechanism;

Figures 5 and 6 are respectively a sectional end elevation and a front elevation of Figure 4;

20 Figure 7 is a cross section on the line 7—7 of Figure 4.

The machine is more particularly designed for forming annular ribs on cylindrical castings as for instance brake drums or integral brake drums 25 and hubs for vehicle wheels. The molds for such castings are usually formed by patterns having draft in an axial direction and therefore any extension of the mold cavity for forming surrounding ribs must be undercut. With my improved machine this undercutting is accomplished by the relative rotation of an annular frame 30 table on which the sand mold is supported and a head extending upward through the central opening in said table into the mold cavity and 35 radially adjustable with respect to the axis of rotation. There is also provision for manually effecting this relative rotation and radial movement so that the operator may quickly perform the undercutting operation.

40 In detail, A is an annular supporting frame mounted upon legs B and provided on its upper face with a circular race groove C for a series of balls D. E is an annular table having a corresponding race groove E' for engaging the balls D and also provided with a depending portion E² having rack or gear teeth E³ on its under face. The table E is further provided with a detachable top plate F for receiving the mold to be operated upon and which is exchangeable to correspond to different sizes or shapes of molds. This plate is axially registered with the table E by means of dowel pins F' depending therefrom and engaging corresponding recesses in the table. The plate F is further provided with upwardly 45 projecting pins F² for engaging sockets in the

flask G for the sand mold so as to properly register the mold with the table.

Extending transversely of the annular frame A are parallel guide rods H which are secured in position by suitable means such as the nuts H' engaging threaded end portions H² and the washers H³ which latter bear against the outer face of the member A. I is a carriage slidably mounted on the rods H within the annular frame A and extending upward to approximately the 5 level of the top face of the table E. I' is a lug projecting upward from the carriage I through the opening in the annular plate F, and J is a detachable head supported on the carriage and centered by the lug I'. This head J has projecting upward therefrom the spaced posts J' to which are secured the opposite ends of a segmental presser member K. The major portion of the outer face of the member K is of a radius 10 corresponding to the inner face of the cylindrical wall of the mold cavity so that when said member is adjusted radially with the carriage I, it will bear or press against this face. However the end portions of the outer face are rounded 15 to avoid scraping or cutting the sand. The member K is not, however, rigidly mounted on the carriage but is yieldably attached thereto by means of headed guide pins K' having a threaded engagement therewith and slidably engaging 20 recesses in said posts J'. Springs L located in recesses in said posts above and below the pins K' and also engaging registering recesses in the member K serve to yieldably press the latter 25 radially outward to the limit permitted by the headed pins. The member K is further provided 30 with a series of slots K² which correspond in position to the location of the annular ribs which are to be formed on the casting. Engaging 35 these slots are cutter blades M the shanks M' of which extend radially inward and are rigidly 40 mounted on the head J. In normal position the cutters M are withdrawn into the slots K². If, however, the member K is held against radial outward movement during the continued movement of the carriage I, the cutters will be projected 45 from the slots so as to engage the sand of the mold. The arresting of the radial outward movement of the member K is effected by a ring N surrounding the inner edge of the annular plate F and projecting upward therefrom. This 50 ring has a beveled top face and the member K is provided with a correspondingly beveled lower face so that when these faces engage each other further outward movement of the member K is arrested. However, relative rotary movement of 55

the ring N in the member K is permitted as will be hereinafter described. The length of the slots K² is sufficient not only to receive the cutter blades M but to leave an opening in advance 5 of the cutting edge thereof through which the sand may be carried inward into a vertical channel K³ through which it can escape.

For the purpose of slicking the sand of the undercut or grooved portions of the mold the cutter blades M are formed both to effect the cutting and the slicking. As shown particularly in Figure 10 4, the portions M² of the end or outer faces of the cutter blades are of a radii respectively corresponding to the faces of the completed undercuts or grooves. However, the forward portions 15 M³ are of smaller radii and furthermore, as shown in Figures 5 and 6 in addition to Figure 4, the forward portions taper forwardly both in radial and axial section. The front ends of the forward 20 portions effect the cutting and the flaring parts of the forward portions M³ in rear of the front end and also the portions M² effect the slicking.

To provide for the fillets which are to be formed 25 at the junctions of the annular ribs and the brake flange, the presser member K is provided in rear of and in peripheral alignment with the slots K² with the beads K⁴, shown particularly in Figures 4, 5, 6 and 7. These beads have their forward ends tapered both radially and axially 30 to freely enter the undercuts or grooves formed by the cutter blades. The portions of the beads in rear of the tapered portions however have a section especially in an axial direction to compact and slick the sand to round the corners and thereby provide for the desired fillets.

To perform the work of cutting the grooves in the mold there must first be a rotation of the table E with respect to the frame and carriage I, and second a radially outward movement of the member K and cutter blades M due to a sliding movement of the carriage I on the guides H. To manually perform both of these movements the following mechanism is provided. O is a shaft which is journaled in a bearing O' in the frame 40 A and projects radially outward therefrom. On this shaft is mounted a gear wheel P which is in mesh with the annular rack or gear teeth E³ on the table. Adjacent to the gear wheel P is a second gear wheel Q which is revoluble on the shaft O and which is in mesh with the complementary gear wheel R on a shaft S parallel to the shaft O and mounted in a bearing S' in the frame A. The outer ends of the shafts O and S are provided with squared or polygonal portions O² and 45 S² which correspond in size and are adapted to receive a corresponding socket T on a hand crank T'. The inner end of this socket T is provided with clutch teeth T² adapted to engage with corresponding clutch teeth Q' on the gear wheel Q, the arrangement being such that when the crank 50 T' is engaged with the shaft O it may either rotate this shaft alone or by moving the clutch teeth T² and Q' into engagement will simultaneously rotate the gear wheel Q. The shaft S has an inward extension S³ which is threaded to 55 engage a nut U in the carriage I. This will cause a movement of the carriage on the guides H whenever the shaft S is revolved either by direct engagement therewith of the hand crank T' or through the medium of the gear wheels Q and R and the clutch engagement between the hand 60 crank T' when mounted on the shaft O. On the other hand, when the crank T' is engaged with the shaft O but has its clutch teeth T² out of engagement with the clutch teeth Q', then the

shaft O alone will be revolved, which through the gear wheel P will communicate rotary motion to the table E.

With the construction as described, the operation is as follows: The sand mold is first formed in the flask G in the usual manner and this flask is then placed upon the plate F and is registered in axial alignment with the table E by means of the pins F². This will also register the ring N with the inner face of the mold cavity. During the placing of the mold upon the plate F and table E the carriage I is in the position where the member K and cutters M are withdrawn radially inward so as to be wholly within the mold cavity and not to interfere with the sand wall. After 15 the flask is properly mounted the operator places the hand crank T' in engagement with the squared portion O² of the shaft O and pushes it inward far enough to engage the clutch teeth T² with the corresponding clutch teeth Q'. The 20 shaft is then rotated by the crank which will simultaneously revolve the table E together with the mold supported thereon and will move the carriage I radially outward on the guides H. This will carry the presser member K outward 25 until its lower beveled edge comes in contact with the upper beveled face of the ring N at which time the outer face of the member K will be in contact with and press against the inner cylindrical face of the mold and thereby prevent damage to this face as well as slick the same. Further outward movement of the member K is then prevented but the continued movement of the carriage will project the blades M from the recesses K² thereby shaving away the sand which is 30 carried inward through the slot and dropped through the channel K³. The blades also compact and slick the sand of the undercuts or grooves. In addition, the beads of the presser member compact and slick the sand at the corners of the undercuts or grooves to provide for the fillets in the casting. During this continued movement, the springs L are compressed. Outward movement of the blades M is also limited, preferably by a stop formed by a rod V projecting rearward from the carriage I parallel to its direction of movement. This rod extends through a bearing W on the frame A and has a threaded end portion for engaging locknuts X. Thus by adjusting these nuts the outward movement of 40 the carriage I may be limited as desired. When this limit is reached the table E may still be revolved by the crank T' provided that the clutch teeth T² are disengaged from the clutch teeth Q'. To withdraw the cutters and presser member K from engagement with the mold, the crank T' is transferred into engagement with the shaft S, and by then rotating the crank in the same direction this will impart a reverse rotation to the screw S³ from that transmitted from the shaft O and this in turn will move the carriage radially inward. During the withdrawal, the presser member K remains in engagement with the sand during the withdrawal of the cutters and then is withdrawn.

What I claim as my invention is:

In a machine for undercutting sand molds, the combination with a presser member engageable with the wall of a mold cavity, of a combined cutter and slick adapted to extend beyond said presser member and having at its front end a solid cutting portion and in rear of said cutting portion a slicking portion for the entire surface and terminating in a rearwardly tapered portion.

FRANK H. LE JEUNE.
